UNITED STATES PATENT OFFICE.

WILLIAM L. RUMMEL, OF SOUTH SIOUX, NEBRASKA.

TRAIN-STOPPING DEVICE.

1,101,664.

Specification of Letters Patent. Patented June 30, 1914.

Application filed March 11, 1912. Serial No. 683,134.

To all whom it may concern:

Be it known that I, WILLIAM L. RUMMEL, a citizen of the United States of America, residing at South Sioux, in the county of 5 Dakota and State of Nebraska, have invented certain new and useful Improvements in Train-Stopping Devices, of which the following is a specification.

My invention relates to methods for controlling by external means the air line of a 10 train by automatically opening valves connected with the air pipe. This is accomplished by the elevation of side rails movably secured to the track rails and adapted 15 to be raised for contact with trucks pivotally secured to engines of the road. The means for operating the movable rails are illustrated and described in a separate application for patent filed, Dec. 1, 1910 Ser. No. 20 595,081 on a railway block system, which provides for the division of the railway track into blocks and sections forming a part of an electric circuit, a movable rail being attached to each track rail in every section. 25 As there shown the electrical current, when closed, holds the movable rails down in the normal position, and when the current is shunted by the entrance of trains into the block the rails are elevated for contact by 30 means of gravity, being restored by the energizing of the current when the train passes out of the block.

The invention consists in the novelty of construction and arrangement and construction 35 of the device as will be hereinafter shown and described.

I have illustrated my invention in the accompanying drawing in which—

Figure 1 is a front elevation of the attachment to the engine to connect with the side rails, a part being broken away and shown in section, showing also a cross-section of track and side rails. Fig. 2 is a plan view of the same. Fig. 3 is a detail view of 45 one of the pivoted arms 42 and 43 showing the manner in which the rods 40 and 41 are supported.

The place and manner of adjustment to the engine will depend upon the particular 50 type of engines used.

In the drawing, 1 and 2 are the track rails and 3 and 4 the respective side rails, the rails 3 being in normal position and the rail 4 being elevated for contact with the 55 trucks. Clamps or braces 5 are secured to the track rails and the side rails are piv-

totally connected thereto by means of arms or links 6, the bolts 7 and 8 securing them together. A frame 9 consisting of longitudinal bars 10 and 10^a and cross bars 11 securing the bars 10 and 10^a together, is adapted to be suspended from the engine in some convenient place. The bar 10 is secured above the bars 11, and the bar 10^a is secured to their lower side. The standards 12 and 13 pivotally depend from the bar 10^a directly over the respective side rails 3 and 4. The wheels 15 and 16 are pivotally suspended from the lower ends of the standards by arms 17 and 18, pins 19 passing through 70 the arms and standards and forming the axis on which the arms move up and down. Plates 20 are secured to the standards below the arms to furnish a rest for the arms and hold the wheels from dropping below a 75 horizontal position. The wheels are each double and free upon axis 21 passing through the outer ends of the arms 17 and 18. To the outer ends of said arms are secured heads of upright plates 22 and 23 80 adapted to strike the respective valve pins or stems 24 and 25 depending from the self-closing spring valves 26 and 27. The wheels are adapted to swing inwardly with the standards, the wheels being in normal 85 position free of the rails 3, which is also in normal position.

One of the wheels is adapted for contact with a rail at all times, depending upon the direction of movement of the train, and 90 in the drawing the right hand wheels 16 is shown in contact with the rail 4, the valve pin 25 being raised by the plate 23, releasing the air through the valve 27. The air enters the valves through the respective train lines 95 28 and 30 and couplings 28^a and 30^a, and returns through the pipes 29 and 31, and couplings 29^a and 31^a, as indicated by the arrows, each side being independent of the other. The couplings are supported on the 100 bar 10 of the frame 9 by the slotted uprights 32 and 32^a and 33 and 33^a.

The lateral movement of the wheels for contact with one of the side rails is under control of the engineer of the train, and 105 either side may be adjusted for contact or released by the following means: To the upper ends of the standards 12 and 13, which pass through the bar 10, are secured the ends of the respective rods 34 and 34^a, the opposite ends of the latter being pivoted to a bar 35 sliding upon the inside cross-bars 11 of

the frame. To the standards are secured nuts 39 between the ends of the rods 34 and 34^a and the bar 10^a to build the rods up above the bar 35 to give the bar 35 a free movement upon the cross-bars. To the middle of the bar 35 is pivoted the point of a T-shaped lever 36 which is pivoted near the middle of its stem to the bar 10^a. To the free ends of the lever 36 are pivoted rods 37 and 38 for the use of the engineer. By pulling the rod 38 the trucks were placed in the position shown in the drawing. The wheels 15 will be brought into position for contact with the rail 3 and the wheels 16 cleared of rail 4 by pulling the rod 37.

After the air has been opened on either side in the manner already described, the valve is held open and released in the following manner: The outer ends of the rods 40 and 41 are pivoted respectively in the slotted uprights 32 and 32^a, and the central parts of the rods pass freely through enlargements 24^a and 25^a on the respective valve pins 24 and 25. Near the opposite ends thereof the rods 40 and 41 pass freely through the slotted uprights 33, and 33^a, while the inner ends of the rods are pivotally connected to pivoted arms 42 and 43 through the respective connecting rods or links 44 and 45, the pivoted arms being pivoted at their lower ends to the respective supports 46 and 47, secured to the bar 10. When the air line is closed and the wheels free of the rail, the pivoted arm, link and rod assume the position shown at the left of the drawing. When either of the side rails and the corresponding wheels are raised and the air valve opened, the pivoted arm, link and rod upon that side assume the position shown at the right of the drawing, the pivoted arm being raised by the action of the valve pin upon rods 40 and 41. They will remain in that position until released, the inner end of the rod resting against the shoulders 42^a and 43^a formed on the pivoted arms 42 and 43, respectively as the latter stand in a vertical position. It will be noted that the rods 40 and 41 are located in the same vertical plane with the shoulders 42^a and 43^a, consequently when the pivoted arms 42 and 43 are in upright position said rods unless otherwise supported will rest upon said shoulders. The pivoted arms when vertical are adapted to be engaged by the respective dogs 48 and 49 secured to the outer ends of the rods 50 and 51, which pass freely through the supports 46 and 47. The inner ends of the rods are pivoted to the forward ends of the respective L-shaped levers 52 and 53 which are each pivoted at the respective angles 54 and 55 to a supporting bridge 56 secured to the central part of the bar 10. The opposite ends of the levers are pivoted by the respective pins 57 and 58 in the transverse slot of a cross-shaped bar 59, the forward end of

which has a longitudinal slot in which it is pivoted to the bridge by a pin 60, the rear end of the bar 59 being free. A coil spring 61 is secured to the front end of the levers 52 and 53 which normally pulls the levers together and restores them and the bar 59 to a central position. To the rear end of the bar 59 is pivoted a lever 62 for the use of the engineer in closing the air valve. By pulling the lever the bar 59 will be moved to the left of the drawing on the pin 60 as a pivot, at the same time sliding forward on the pin. The forward sliding movement is caused by the pin 70 riding over the face 71 of a cam 72 secured to the frame 10. This movement of the bar pushes forward the rear ends of the levers 52 and 53 on the pivots 57 and 58. The forward ends of the lever are thus each thrust outwardly, moving outwardly the rods 50 and 51 and the dogs 48 and 49. The movement of the dogs kicks away whichever of the pivoted arms 42 or 43 that is in an upright position, causing it to assume the position of the arm 42. At the same time the rod which holds the air valve open will drop and the valve will close. At the end of the movement just described the action of the spring 61 pulls together the forward ends of the levers 52 and 53 and restores the whole device to normal position.

I have not illustrated the valve referred to in the above specification for the reason that such valves are of well known construction and any form of self-closing valve may be used in connection with the rest of the device.

I do not wish to limit myself to the particular construction here shown but aim in the following claims to cover all modifications and changes which are within the spirit and scope of my invention.

Having described my invention, what I claim as new and desire to secure by Letter Patent, is,—

1. In a railway block system, the combination with a track and vertically movable track obstacles located adjacent thereto and on both sides, of a frame adapted for attachment to engines of the road, wheels pivotally supported from the frame above the track obstacles and having both a vertical and a lateral movement so that each is adapted for contact with a track obstacle and each is free of the other for vertical movement, means for laterally moving the wheels, pipes connecting with the air line of the train, valves in said pipes and means connected therewith for opening the valves by contact with the wheels when raised and means for closing the valves.

2. In a railway block system, the combination with a track and track obstacles, of a frame adapted for attachment to a locomotive engine, wheels pivotally suspended from

- the frame having a vertical and a lateral movement and adapted for contact with the track obstacles, means for moving said wheels so that one of them will engage one of said track obstacles and the other be free of engagement with the corresponding track obstacle and vice-versa, pipes connecting with the air line of the train, valves in said pipes and valve stems projecting from the valves for opening said valves, plates connected with the wheels for contact with the valve stems, arms for holding the valve stems open when opened by the wheels and levers for releasing said arms.
5. In a railway block system, the combination with track and track obstacles, of a frame adapted for attachment to a locomotive, wheels pivotally suspended from the frame having a vertical and a lateral movement, each of said wheels being adapted to contact with one of said track obstacles, the other of said wheels being at the same time free of engagement with the corresponding track obstacle, means for alternately moving said wheels in a lateral direction to make and break contact with said track obstacles, pipes connecting with the air line of the train, valves in said pipes, valve stems extending from the valves for opening the valves, plates connected with the wheels for contact with the valve stems, pivoted arms
- for retaining the valve stems in open position, and levers for releasing said pivoted arms.
4. In a railway block system, the combination with track rails and side rails the said track and side rails being connected by means of links and adapted to be raised beside the track rails, of a frame adapted for attachment to a locomotive, wheels pivotally suspended from the frame above the side rails and having a vertical and a lateral movement, means connecting the wheels for lateral movement together so that each is adapted for contact alternately with a side rail and each being free of the other for vertical movement, means for laterally moving the wheels, pipes connecting with the air line of the train, valves connected with said pipes and means connected with said wheels for contact with the valves whereby the valves are opened, means connected with the valves for holding them open and means for releasing said valve holding means, substantially as described.
